CLOTHES HANGER ATTACHMENT
John H. Moorhouse, Clear Lake, Minn.
Filed Nov. 5, 1959, Ser. No. 851,035
4 Claims. (Cl. 223—91)

This invention relates to an attachment for use in connection with an ordinary type of clothes hanger, such as a wire clothes hanger, to provide support for a garment hung thereon and to prevent such a garment from slipping on said hanger. Such a clothes hanger is commonly used by clothes cleaning and pressing establishments.

It is common practice to place a paper guard over the cross bar or hanging bar of a clothes hanger, such as of a wire clothes hanger, to provide more adequate support for a garment hung thereon, such as a pair of trousers, and to prevent creasing of such a garment. Such a paper guard provides more adequate support than does the bare clothes hanging bar of the hanger but such a support does not prevent slippage of the garment off of the bar. Such a support, moreover, is completely covered by the garment hung thereover preventing any indicia on said support from being visible and having advertising value while the hanger is in use.

It is desirable to have some means in addition to such a supporting member as a paper guard whereby a garment such as a pair of trousers may be hung on a hanger without it being creased and without having the tendency to slip off of the hanger.

It is an object therefore of this invention to provide an attachment to be used in connection with a clothes hanger, such as a wire clothes hanger, to provide support for a garment being hung over the cross bar of said hanger and to provide means to prevent slippage of said garment, and further to have a portion of said invention visible in operating position to have indicia such as advertising material present thereon.

It is another object of this invention to provide an attachment to be used in connection with a clothes hanger comprising a member of relatively rigid sheet material having a portion adapted to overlie the cross bar of said clothes hanger to provide adequate support for a garment to prevent creasing of said garment and a clamping bar extending substantially the full length of said hanger adapted to overlie the outer side of said garment to hold said garment in position to prevent its slippage.

It is a further object of this invention to provide an attachment for use in connection with a clothes hanger comprising an elongated substantially rectangular sheet of suitably rigid material adapted to have a portion thereof reversely curved to overlie the cross bar of said hanger and having a portion thereof depending from said cross bar and having a flap portion cut from said depending portion having one end connected thereto and having its other end adapted to provide locking engagement with the adjacent portion of said depending portion whereby said flap portion may be placed to overlie a garment hung over the cross bar of said hanger with the free end of said clamping portion being releasably secured to the depending portion adjacent thereto.

It is still a further object of this invention to provide an attachment for use in connection with a clothes hanger comprising a portion adapted to be slidably secured to the cross bar of said hanger adjacent one end thereof, said portion having an elongated strip of narrow width forming a clamping member pivoted at one end thereto and a second portion of said attachment on said cross bar spaced from said first portion having means in connection therewith for releasably engaging the free end of said clamping member at certain different points there-

2

on whereby a garment may be hung over said cross bar between said portions and said portions may be adjusted to be adjacent either side of said garment and said clamping portion is adapted to overlie an outer side of said garment with the free end thereof adapted to be releasably secured at certain different points thereon to said second portion.

These and other objects and advantages of the invention will be fully set forth in the following description made in connection with the accompanying drawings in which like reference characters refer to similar parts throughout the several views and in which:

FIG. 1 is a view of applicant's device in front elevation in operating position showing a portion of a garment hanging thereon;

FIG. 2 is a broken view in partial horizontal section taken on line 2—2 of FIG. 1 as indicated by the arrows;

FIG. 3 is a view similar to that shown in FIG. 1 with a portion broken away showing a modification of applicant's device;

FIG. 4 is a fragmentary view in partial horizontal section taken on line 4—4 of FIG. 3 as indicated by the arrows;

FIG. 5 is a view in side elevation with a portion thereof broken away showing a modification of applicant's device;

FIG. 6 is a fragmentary view in partial horizontal section taken on line 6—6 of FIG. 5 as indicated by the arrows;

FIG. 7 is a view in side elevation with a portion broken away showing a modification of applicant's device;

FIG. 8 is a blank shown in plan indicating a die cut of applicant's device as shown in FIG. 1;

FIG. 9 is a plan view of a blank indicating a die cut of applicant's device as shown in FIG. 3;

FIG. 10 is a top plan view taken on line 10—10 of FIG. 7 as indicated by the arrows;

FIG. 11 is a view in vertical section taken on line 11—11 of FIG. 1 as indicated by the arrows;

FIG. 12 is a view in vertical section taken on line 12—12 of FIG. 5 as indicated by the arrows;

FIG. 13 is a view in vertical section taken on line 13—13 of FIG. 7 as indicated by the arrows;

FIG. 14 is a view in vertical section taken on line 14—14 of FIG. 7 as indicated by the arrows;

FIG. 15 is a view in front elevation of another modification of applicant's device indicating a portion of a garment disposed thereon;

FIG. 16 is a view in horizontal section taken on line 16—16 of FIG. 15 as indicated by the arrows;

FIG. 17 is a view in front elevation of a portion of applicant's device; and

FIG. 18 is a view in vertical section taken on line 18—18 of FIG. 15 as indicated by the arrows.

Referring to the drawings and particularly to FIGS. 1, 2, and 8, a clothes hanger 10 is shown. Said clothes hanger having a cross bar 12 is an ordinary type of wire hanger such as is commonly used by dry cleaning and pressing establishments. In connection with said hanger 10 there is shown a blank 13 which may be formed of any suitable sheet material and it has been found that substantial rigid paper sheet material is suitable. Said blank 13 will have its upper portion 14 reversely curved as along the dotted line 15 with said curved portion being disposed over the cross bar 12 to provide a suitable supporting surface for a garment such as garment 16 and has a sufficiently rounded upper surface so that said garment 16 will not become creased thereon. Said reversely curved portion may be fastened as by staples 17. Said blank 13 will have a depending portion 18 at one side of said hanger as shown in FIG. 1. Die cut from said depending portion 18 along the line 20 is a strip clamping

portion 22 which is releasably secured to the adjacent side of the cross bar 12. The portion 18 is spaced from the portion 14 so that the garment 16 may be hung over the cross bar 12 with the portion 14 overlying the garment 16 and the portion 18 secured to the adjacent side of the cross bar 12. The portion 18 is releasably secured to the adjacent side of the cross bar 12 by staples 24.

member 21. Said clamping member 21 will be integral with said depending portion 18 at one end thereof to have a hinged effect therewith and will have a fastening means here shown in the form of a hook 22 at its free end adapted for locking engagement with the hook portion 23 formed in the adjacent portion of said depending portion 18. Said blank 13 will be formed of a sufficiently bendable material so that member 21 may be bent outwardly to an open position to permit garment 16 to be draped over the cross bar 12. Said clamping strip 21 is then returned to closed position to overlie the garment and its free end will be lockingly engaged with the hook portion 23. The garment will then be frictionally engaged by the clamping portion 21 in connection with the depending portion 18 along the line 20. There is sufficient hold here to prevent the garment from slipping.

Indicia such as advertising indicia 24 is preferably placed on said clamping strip 21. Said clamping strip is well adapted for advertising purposes as it is exposed and clearly visible at such times as a garment is draped over the cross bar of a hanger and thus contributes utility to applicant's invention which may inure to the benefit of whomever may provide the attachment such as a cleaning service.

With reference to FIGS. 3, 4, and 9, a modification of applicant's device is shown in which a blank 25 is provided having an upper portion 26 thereof adapted to be reversely curved along the line 27 to form a portion to be disposed over the cross bar 28 of which only a fragmentary view is shown and this will be of a common and ordinary type of wire hanger 29, such as hanger 10. Said reversely curved portion may be secured to the body portion of the blank 25, as by staples 30. Said blank 25 will be die cut along lines 32 and 33 to remove a triangular portion and form an elongated clamping strip 36 having a tongue 37 of reduced width extending outwardly at its free end with a small hook portion being formed at the free end of said tongue. Cut into the body of said blank 25 adjacent the end of the strip 36 are parallel slits 39 through which the tongue 37 may be disposed, as indicated in FIGS. 3 and 9, to form a holding means. When the clamping strip 36 is raised to have its tongue portion 37 disposed through the slits 39, the hinged portion 40 of the strip 36 will buckle slightly as indicated in FIG. 3. As is seen, said clamping strip 36 is here shown die cut on a slant to provide sufficient length to have said tongue portion disposable through said slits 39.

With reference to FIGS. 5 and 6, another modification of applicant's device is shown in which a blank 45 is provided similar to the blanks shown in FIGS. 8-9 having an upper reversely curved portion 46 disposed over the cross bar 47 of a hanger 48 and being secured as by staples 49. A portion 50 of said blank 45 will depend somewhat below the cross bar 47. Adapted to overlie a lower longitudinal portion of said depending portion 50 is a clamping strip 52 secured to said depending portion 50 at one end thereof, as by rivets 53, and having at its free end an aperture 55. Adapted to be in alignment with said aperture 55 and secured to said depending portion 50 is a button-like member 57 having an enlarged head portion 58 to be disposed through said aperture 55 for removably securing the free end of said clamping strip 52.

With reference to FIGS. 7, 10, 13 and 14, a clothes hanger 60 is indicated of the type similar to clothes hanger 10 having a cross bar 61. Adapted to be disposed over said cross bar 61 adjacent one end thereof is a substantially cylindrical member 62 formed of a resilient material, such as of plastic, having a bore 63 therethrough of small transverse dimension and having a radial slit 64 extending from said bore to the periphery of said member 62. As indicated in FIG. 13, one side of said member 62 will be somewhat flattened and extending outwardly

therefrom the length of said bar 61 is a clamping strip 65 having a plurality of apertures 66 longitudinally spaced along the free end portion thereof.

Adapted to be mounted on said cross bar 61 adjacent its other end is a cylindrical member 68 of substantially short length having a bore 69 therethrough of small transverse dimension and having a radial slit 70 extending from said bore to the periphery thereof. Said bores 63 and 69 will be of such a size that when said members 62 and 68 are mounted on said cross bar 61 they will frictionally engage said cross bar. Said member 68 is provided with a substantially flat side 72 having extending outwardly therefrom a button-like member 74 having an enlarged head portion and a neck portion of reduced dimension adapted to be disposed through any certain one of said apertures 66 to grippingly engage the free end of said clamping strip 65 to hold the same in a locked position.

In use, said members 62 and 68 will be mounted on said cross bar 61 and it is seen that they are capable of sliding adjustment thereon to be positioned certain different distances apart. They may be adjusted so as to abut either side of a garment 76 hung over said cross bar 61 and said clamping strip 65 is then positioned over an outer side of said garment and secured to said fastening member 74 for clamping said garment 76 in position against the cross bar 61 to prevent it from slipping off of said cross bar.

Referring to FIGS. 15-18, another modification of applicant's device is shown in connection with a clothes hanger 75 having a cross bar portion 75a. A blank 85 is provided similar to said blank 13 having a reversely curved portion 77 disposed over the cross bar 75a and secured in position by fastening means 79 shown here in the form of staples. Although this specific structure is here indicated, there is embodied within the applicant's invention the concept of having said blank 85 disposed over cross bar 75a to have equal portions at either side thereof and having identical construction at either side thereof.

Said blank 85 has a depending portion 78 extending substantially the full length of the hanger 75, and adapted to overlie said depending portion is a clamping strip 81 secured at one end thereof as by a staple 80 to adjacent one end portion of said depending portion 78, and having adjacent its other end extending upwardly from its lower edge portion a plurality of open-ended slots 82. At the other end portion of said depending portion 78 is a plurality of slits 84 through one of which may be conveniently disposed the free end portion of said clamping strip 81 with one of said slots 82 being disposed in said slit to releasably hold in operating position the free end portion of said strip 81.

Thus in operation a garment 83 will be hung on hanger 75 folded over the cross bar 75a and overlying applicant's blank 85 whereby said clamping strip 81 will be disposed about the outer side of said garment with the free end of said strip 81 being disposed through one of the slits 84 depending on the width of the garment 83 to releasably hold said garment securely on said hanger. The bulk of the garment will determine which of the slots will engage said slit. If desired, said strip 81 may be disposed at either side of said blank 85 to provide a holding means for either side of a garment.

Thus is seen that I have provided a very simply constructed attachment for an ordinary type of clothes hanger whereby garments such as trousers hung over the cross bar of such a hanger are held securely in position as to prevent any tendency of the garment to slip off of the cross bar.

It will of course be understood that various changes may be made in the form, details, arrangement and proportions of the parts, without departing from the scope of applicant's invention, which, generally stated, consists in a device capable of carrying out the objects above set

forth, in the parts and combinations of parts disclosed and defined in the appended claims.

What is claimed is:

1. A garment clamping attachment for use in connection with a clothes hanger having a cross bar comprising a substantially rectangular member of stiffened sheet material having a width substantially the length of said cross bar, one end portion of said member being reversely folded over said cross bar, the remaining portion of said member depending from said cross bar, a transversely extending flap portion being struck from said depending portion and having one end integral with said depending portion and having its other end free and formed inwardly of the adjacent side of said depending portion, and means formed in said adjacent side of said depending portion for locking engagement with said free end portion of said flap.

2. The structure set forth in claim 1, the free end portion of said flap portion and said means in said adjacent depending portion being formed as inter-engaging hook portions.

3. A garment clamping attachment for use in connection with a clothes hanger having a cross bar comprising a substantially rectangular member of stiffened sheet material having a width substantially the length of said cross bar, one end portion of said member being reversely folded over said cross bar, the remaining portion of said member depending from said cross bar, a longitudinally extending flap portion having one end integral with said depending portion and being struck therefrom at a downwardly extending angle with relation to the lower edge portion of said depending portion whereby a flap portion is formed having a length greater than the width of said

depending portion, a hook formed at the free end of said flap portion, a slit formed in said depending portion in horizontal alignment with the secured end of said flap portion for engagement with the free end of said flap portion to form a transversely extending clamping member to be disposed at the outer side of a garment hung on the cross bar of said hanger.

4. A garment clamping attachment for use in connection with a clothes hanger having a cross bar comprising a member formed of an elongated sheet of stiffened material having a width substantially the width of said cross bar, said member having a portion reversely curved to be disposed over said cross bar for forming a hanger guard thereover, the remaining portion of said member depending from said cross bar, a flap of greater length than the width of said depending portion extending thereacross having one end integral with said depending portion at one side thereof, a plurality of downwardly extending open-ended slots at the free end of said flap, and a slit in said depending portion adjacent its other side for engagement with the free end of said flap arranged and constructed to receive one of said slots therein to removably secure the free end of said flap.
